UNITED STATES PATENT OFFICE.

EARL A. REED, OF OKEMAH, OKLAHOMA.

ROTARY WELL-DRILLING APPARATUS.

Application filed February 27, 1925. Serial No. 12,070.

The invention relates to improvements in rotary well drilling apparatus.

It is an object of the invention to provide an improved form of carrier for supporting 5 rotatable cutters in a bit head, with detachable means for retaining said carriers in the bit head. More specifically, the invention comprehends a bit in which the rotary bit carriers are of a large diameter 10 and supported at each end in the bit head by detachable pins of lesser diameter.

The carriers provide a large bearing for the cutters, permitting cutters to be used that are manufactured from tubular stock without 15 necessitating the use of interposed bushings. It is apparent that when cutter teeth are destroyed the cutter is useless and if the cutter is composed of solid bar stock the material forming the body thereof is wasted. 20 This invention includes cutters to be used that are made from tubular stock wherein little material is wasted in the body of the cutter and at the same time eliminates the use of interposed bushings or bearings between 25 the supporting pins and the cutters.

Referring now more particularly to the drawings wherein like reference characters indicate corresponding parts, Figure 1 designates a view with parts in section of a 30 drill bit;

Figure 2 illustrates a detailed view of the carrier and its supporting pins for the center cutter;

Figure 3 is a view of one form of carrier 35 for the side cutters; and,

Figure 4 is a view of a different form of carrier for supporting another type of cutter.

Referring now more particularly to the 40 drawings wherein like reference characters indicate corresponding parts, the numeral 1 designates a bit head having an orifice or opening 2 leading therethrough for the passage of water or other substances, this opening communicating with the branches 3 and 4 for applying the water to parts of the drill to be later described. The lower part of the bit head is provided with recesses 5 and 6, the recesses 5 being fashioned to receive the side cutters 7 and 8 while the recess 6 receives the cross cutters 9 as is common 45 in the art.

The cutters are all composed of high grade 50 steel or similar material. As soon as the cutting teeth are damaged these cutters are worthless. It is therefore apparent that

when the cutters are manufactured from solid bar stock the substantial quantity of material forming the body thereof is wasted whenever a cutter is destroyed. The present 60 invention aims to utilize cutters made from tubular stock so that little material is utilized in the body thereof resulting in but a slight loss when a cutter is discarded. It is one of the salient features of this invention to 65 utilize cutters so made without at the same time employing enlarged bushings or the like for supporting such cutters.

In carrying out this invention I provide 70 carriers for either or both the side cutters and the cross cutters. In Figure 2 I have shown the carrier for the cross cutters. This carrier is represented by the reference character 10 being composed of a block of metal or the like capable of withstanding drilling 75 pressures and strains and having in each side thereof threaded sockets 11. These sockets receive supporting pins 12 having threads adapted to engage the threads of the sockets 11. When in use a series of the cutters 9 are 80 mounted on the carrier 10 rotating therearound. The carrier is positioned within the bit head, lying against the inner side walls thereof and is retained in position by the pins 12 passing through openings in the side 85 walls. Dowel pins 13 may be used for retaining the carriers in the bit head and for holding them against rotation, it being appreciated that the cutters rotate around the carriers. As before stated, these cutters may 90 be constructed of tubular stock and therefore have bodies of the least possible thickness yet sufficient to withstand drilling strains and stresses. Washers may be placed on the carrier 10 on each side of the cutters arranged thereon should this construction be 95 found desirable as is, of course, common in the art.

The angular or side cutters 7 are similarly 100 mounted. As shown in Figure 3 a carrier 14 is provided which is formed with threaded sockets 15 receiving the supporting pins 16. The periphery of the carrier is provided with a shoulder 17 receiving a cutter having its inner surface similarly formed so as to 105 prevent the cutter from sliding off the carrier and causing wear in the pocket of the bit head particularly where it is not desirable to use washers between the bit head and the cutter. The side cutters are mounted on 110 their carriers and the carriers then inserted in the side sockets 5 of the bit head and the

pin 16 then threaded into the carriers engaging, of course, the walls of the side sockets. The side cutters are placed in the bit head before the center cutters. Dowel pins 5 are used for retaining the supporting pin 16 and the carriers 14 in position. The cutters provided with the shoulders 17 rest on the periphery of the carriers 14 and rotate there-around. These cutters have a large open 10 interior because of the diameter of the carriers 14 and can therefore be constructed from tubular stock.

In Figure 4 of the drawings I have shown another form of carrier for the side cutters, 15 this carrier being adapted to support a frusto conical cutter. Obviously the carriers can be of any contour depending upon the type of cutter that is to be used.

It will be seen, however, that the carriers 20 are of a substantial diameter as compared with their supporting pins and that these pins detachably unite the carriers to the bit head. Any carrier with its cutter can be removed by the removal of the supporting 25 pins for the replacement of a new cutter. It will furthermore be seen that no bushings need be employed to support the cutters, yet at the same time cutters are employed that are manufactured from tubular stock.

30 It will be understood that various forms of carriers may be used for supporting these cutters, that the carriers may vary in con-

tour, size, etc., without departing from this invention, and also any type of cutter may be used on the carriers.

Having thus described my invention, what I claim is:

In a well drilling tool, the combination with a drill head having an inclined pocket therein communicating with a source of liquid supply, of a rotary cutter located within the pocket comprising a replaceable thin annular shell constructed of tubular stock and having a toothed periphery, a one-piece massive-like supporting member conforming to 45 the contour of the internal surface of the replaceable shell and whereon said shell has a free rotary bearing support, the supporting member having a cut-out portion defining a recess on one side thereof and a shoulder on the other side thereof with the shoulder located in substantially the central plane of the supporting member, said thin replaceable rotary cutter being of complementary 50 formation whereby the shoulders of the support and shell respectively prevent lateral disengagement in a downward direction of the shell relative to the support, said shell being prevented from lateral disengagement 55 in an opposite direction by the wall of the said inclined pocket formed in the drill head. 60

In testimony whereof I affix my signature.

EARL A. REED.
